(57) **CLAIM**

The ornamental design for a display screen or portion thereof with animated graphical user interface, as shown and described.

DESCRIPTION

FIG. 1. is a first image of a display screen or portion thereof with animated graphical user interface showing our new design;

FIG. 2. is a second image thereof;

FIG. 3. is a third image thereof;

FIG. 4. is a fourth image thereof;

FIG. 5. is a fifth image thereof;

FIG. 6. is a sixth image thereof;

FIG. 7. is a seventh image thereof;

FIG. 8. is an eighth image thereof;

FIG. 9. is a ninth image thereof;

FIG. 10. is a tenth image thereof; and

FIG. 11 is a first image of a second embodiment of a display screen or portion thereof with animated graphical user interface showing our new design;

FIG. 12 is a second image thereof;

FIG. 13 is a third image thereof;

FIG. 14 is a fourth image thereof;

FIG. 15 is a fifth image thereof;

FIG. 16 is a sixth image thereof;

FIG. 17 is a seventh image thereof;

FIG. 18 is an eighth image thereof;

FIG. 19 is a ninth image thereof; and,

FIG. 20 is a tenth image thereof.

The appearance of the animated image sequentially transitions between the images shown in FIGS. 1-10 and 11-20. The process or period in which one image transitions to another image forms no part of the claimed design.

The broken lines illustrate a display screen or portion thereof and forms no part of the claimed design. The remaining
